United States Patent Office

Des. 185,527
Patented June 23, 1959

185,527

ASH TRAY

John D. Aye, Seattle, Wash.

Application February 14, 1958, Serial No. 49,638

Term of patent 3½ years

(Cl. D85—2)

Fig. 1

Fig. 2

Fig. 3

Fig. 1 is a perspective view of an ash tray embodying my new design.

Fig. 2 is a top plan view thereof.

Fig. 3 is a central cross-sectional view thereof taken lengthwise of the central pedestal.

I claim:

The ornamental design for an ash tray, as shown.
